(57) **CLAIM**

The ornamental design for a building structure for harvesting pollution as shown and described.

DESCRIPTION

FIG. 1 is a front left perspective view of a building structure for harvesting pollution;

FIG. 2 is a front view thereof;

FIG. 3 is a top view thereof;

FIG. 4 is a left view thereof;

FIG. 5 is a right view thereof; and,

FIG. 6 is a rear view thereof.

The broken lines illustrate portions of the building structure for harvesting pollution that form no part of the claimed design.

1 Claim, 6 Drawing Sheets
